UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE ATTACHMENT.

1,413,835.

Specification of Letters Patent. Patented Apr. 25, 1922.

Application filed April 11, 1919. Serial No. 289,332.

To all whom it may concern:

Be it known that I, ALBERT H. DE VOE, a citizen of the United States, residing at Westfield, in the county of Union and State 5 of New Jersey, have invented certain new and useful Improvements in Sewing-Machine Attachments, of which the following is a specification, reference being had therein to the accompanying drawings.

10 This invention relates to sewing machines and has for one of its objects to provide a machine capable of hemming a strip of fabric and simultaneously uniting thereto at a single operation a previously hemmed strip.

15 Another object of the invention is to stitch a straight strip of fabric of greater width than the gauge of the needles, at a uniform distance from the edges thereof, and to unite thereto a second piece of fabric placed 20 beneath said strip.

A still further object is to stitch together two pieces of fabric, one piece being buckled to form a pocket between the two pieces.

The invention may be advantageously embodied in machines for forming overall suspender straps wherein strips of fabric are 25 hemmed and united, one with the other, at an angle thereto.

In the manufacture of suspender straps it 30 has heretofore been customary to hem each strap separately and later to unit the crossed straps by a separate operation, whereas, by means of the present construction, the separate uniting operation is eliminated, the 35 hemming seams affording the means for securing the crossed straps together.

The objects of the invention are attained in the present machine wherein a strip-folder is employed to present to the stitching 40 mechanism strips of fabric having both edges folded. This folder is spaced above the cloth-plate and is formed in the upper wall with a longitudinal aperture through which a portion of the fabric protrudes when 45 the strip is of greater width than the delivery end of the folder.

For the purpose of uniting a previously hemmed strap to the strip being hemmed, there is provided a second aperture through 50 the opposite wall of the folder and a treadle-operated tucking element, which normally lies beneath, and in line with, the apertures in the folder, and which may be raised to force the finished strap up into 55 the protruding portion of the strip being

hemmed and into direct contact with said strip, so that as the stitching proceeds the two straps will be united flatwise.

In the accompanying drawings which form a part of this specification, Fig. 1 is 60 a front elevation partly in section of a machine embodying the present invention. Fig. 2 is an end elevation thereof with the cloth-plate shown in section. Fig. 3 is a sectional plan view with the overhanging 65 arm broken away. Fig. 4 is an enlarged sectional view, taken on line 4—4 of Fig. 3, showing a finished strap inserted beneath the strip-folder. Fig. 5 is a similar view showing the finished strap forced up into 70 the protruding portions of the strip being hemmed. Fig. 6 is a view of two united straps constituting one of the products of the present invention. Fig. 7 is a sectional view of two fabrics united so as to produce 75 a pocket, constituting another product of the present invention.

In the preferred embodiment of the invention as illustrated, the machine is constructed with a frame having a base 1, standard 2 and overhanging arm 3 terminating in the hollow head 4. Journaled in the base 1 is the main or driving shaft 5 actuating through suitable mechanism, indicated generally as 6, the needle-bar 7 85 carrying spaced needles 8.

Cooperating with the needles in the formation of stitches are the loopers 9, one only of which is shown, which are actuated from the main-shaft 5. Fabric-feeding mechanism of usual construction, indicated by the numeral 10, is also actuated from the main-shaft 5.

The hollow head 4 is provided with a face-plate 11, to which is pivoted, at 12, a folder 95 supporting arm 13 carrying at its lower end a fabric-guide in the form of a strip-folder 14, spaced above the cloth-plate to afford a free and unobstructed passage between the two. This strip-folder is held in its operative position by a spring-pressed plunger-pin 15 fitted within a socket in the arm 13 and entering a suitable opening in the face-plate 11 but may be swung vertically, to a retracted position shown in dotted lines in Fig. 2. The strip-folder 14 is tapered from its receiving end to its delivery end and is formed with edge-folding scrolls 16, which deliver to the stitching mechanism a folded strip of which the outer edges ex- 110

tend slightly beyond the outer needles. The upper wall, or roof 17 which connects the two folding scrolls is cut away to form a longitudinal aperture 18 through which the material protrudes when the strip is of greater width than the delivery end of the folder, as indicated in Fig. 4 wherein the strip *a* is shown with its marginal portions folded at *b* and its central portion *c* buckled 10 and protruding through the aperture 18 due to the crowding action of the walls 19 on the edges *d* of the strip *a*. The folder 14 is also formed with a fabric-supporting and forming wall 17' provided with a longitudinal aperture 18' in register with the aperture 18.

A connecting member 20 is located intermediate the supporting arm 13 and the folder 14 and is formed with an arched portion 21 which constitutes, in effect, a continuation of the aperture 18.

The presser-foot 22 which acts in conjunction with the feeding mechanism is fixed upon the presser-bar 23 and comprises a bifurcated supporting shank 24, of well known form, which carries a pair of presser-members 25, provided with needle-holes 26, upturned toe-portions 26' and fabric-guides 27. These fabric-guides are provided with 30 vertical guiding walls 28 which act to hold the portion *c* of the strip *a* out of the paths of reciprocation of the innermost needles.

By this construction the strips are stitched at a predetermined distance from the edges 35 thereof regardless of their varying width.

Provision is also made for uniting a previously hemmed strap *e* to the strip *a* being stitched, to form the usual cross-strap, which consists of placing the strap *e* on the 40 cloth-plate 29, beneath the strip-folder and at an angle thereto, so that as the hemming of the strip *a* continues the strap *e* will be simultaneously united to it by common seams. As the straps, at the point where 45 they are united, are ordinarily of a greater width than the folder, the portion *c* of strip *a* will be buckled so as to protrude through the aperture 18 as shown in Fig. 4.

Means are provided for forcing the under 50 or finished strap *e* up into the buckled part of the strip *a* to make it conform to the contour of the latter so that when the two are united they will both lie flat. See Figs. 5 and 6.

55 This means comprises a tucking element, in the form of a blade 30, having a portion 30' projecting above the surface of the cloth-plate, and fixed to a slide-rod 31 mounted to move vertically in a bearing bracket 60 32 depending from the cloth-plate 29. The blade 30 normally rests beneath and in line with the apertures 18 and 18' in the folder 14, and may be raised against the action of the spring 33, through a slot 34 in the cover- 65 plate 35, carried by the cloth-plate 29, and

through the apertures 18'-18 to the position shown in Fig. 5, for the purpose described. A rock-lever 36 is fulcrumed at 37 to a bracket 38 sustained by the cloth-plate, and is connected at its forward end by a link 39 70 to a collar 40 fixed to the slide-rod 31, whereby, through the manipulation of a suitable treadle, not shown, and treadle connection 41, the lever 36 and blade 30 may be caused to assume the positions shown in dotted lines, 75 Fig. 1.

The bracket 38 is formed with an extension 42, fitted with an adjustable plate 43 carrying a stop-pin 44 with which the rear end 36' of the lever 36 may contact, thus limiting the upward movement of the blade 30 80 to a predetermined position dependent upon the width of the fabric being folded.

The stop-pin is lowered to an inoperative position when tapered strips are being 85 hemmed, as the amount of the buckled portion will be constantly changing due to the change in width of the strip, and the blade 30 is kept under control by the treadle connection to hold the finished strap, at all times, 90 in contact with said buckled portion.

When it is desired to stitch together two pieces of fabric so as to produce a pocket *f*, as shown in Fig. 7, the tucking element is 95 not brought into action and the lower fabric *g* is therefore not forced into contact with the buckled portion of the upper fabric *h* so that when the two fabrics are united the desired pocket will be formed.

While the machine has been shown employing four needles, the strip-folder shown to produce hem folds, and the stitching of suspender straps particularly described, it is obvious that a greater or less number of needles may be employed and that other forms 105 of edge folds and various other articles may be produced without departing from the spirit of the invention.

It is further obvious that this invention 110 contemplates broadly the inserting of one fabric within the buckled portion of another fabric to which it is to be united and it is therefore immaterial whether the tucking element be fixed in operative position in register with the apertures in the folder or 115 whether either the folder or the tucking element be retracted one from the other for introduction of the work.

Having thus set forth the nature of the invention, what I claim herein is—

1. In a sewing machine including stitching mechanism, a folder having longitudinal apertures through one of which a portion of a fabric passing therethrough may protrude, and means for inserting a second piece of 125 fabric through said apertures and within said protruding portion, said last-mentioned means comprising a tucking element carried by a vertically movable rod adapted to be elevated, to cause the last-mentioned fabric 130

to conform to the contour of the first-mentioned fabric, whereby the fabrics are passed to the stitching mechanism and united with their adjacent surfaces in contact.

5. 2. In a sewing machine, a folder having apertures through one of which a portion of a fabric may protrude, and means for inserting a second piece of fabric within said protruding portion of fabric, said means including a tucking element in register with the apertures in the folder and adapted to project the fabric therethrough.

10. 3. In a sewing machine including stitching mechanism, a folder having edge-folding scrolls and an aperture extending in the direction of its length, through which a portion of a fabric may protrude, and means intermediate said folding scrolls for inserting a second piece of fabric within the protruding portion of fabric during the stitching of the first-mentioned fabric whereby the two fabrics are positioned to be united by the stitching mechanism.

15. 4. In a sewing machine including a cloth-plate, stitch-forming mechanism and fabric-feeding mechanism, a fabric-guide having a longitudinal aperture and adapted to receive a strip of fabric of a substantially greater width than said fabric-guide and to fold the marginal portions thereof at a uniform distance from its edges, said fabric-guide being supported above said cloth-plate and maintained in spaced relation therewith to afford a free and unobstructed passage between said fabric-guide and said cloth-plate thereby permitting the introduction beneath said fabric-guide of a second piece of fabric extending laterally beyond the edges of the fabric-guide whereby the two may be united, 20 by the stitch-forming mechanism and a presser-foot movable relatively to said fabric-guide.

25. 5. In a sewing machine comprising a cloth-plate, fabric-feeding mechanism and stitch-forming mechanism including spaced needles, a fabric-guide supported independently of said cloth-plate and maintained in spaced relation therewith and adapted to buckle a strip of fabric passing therethrough and to 30 fold the marginal portions thereof and direct them to the respective needles, and means for presenting to the stitch-forming mechanism a second strip of fabric disposed at an angle to said first-mentioned strip with 35 one face thereof in contact with a face of the latter whereby the stitch-forming mechanism operates to stitch the folded marginal portions of the first strip of fabric and to simultaneously unite therewith, at an angle 40 thereto, the second strip of fabric.

6. In a sewing machine, a folder having a longitudinal aperture through which a portion of a fabric protrudes, means for inserting a second piece of fabric within said protruding portion of fabric, said means in-

cluding a vertically movable tucking element and an adjustable stop for limiting the movement of said element, whereby the latter may be raised to a predetermined position dependent upon the width of the fabric 70 being folded.

7. In a sewing machine, in combination, fabric-feeding mechanism, stitch-forming mechanism including spaced needles, a presser-foot having spaced presser-members each 75 provided with an upturned toe-portion, a folder having a longitudinal aperture, means for buckling a portion of a strip of fabric therein through said aperture, and means in advance of said needles and independent of 80 said toe-portion for holding said buckled portion of fabric out of the needle-paths, said last named means comprising fabric-guides carried by the presser-members and having vertical guiding walls between which the 85 fabric is fed.

8. In a sewing machine, a vertically movable folder having apertures through one of which a portion of a fabric may protrude, means for inserting a second piece of fabric 90 within said protruding portion of fabric, said means including a tucking element adapted to enter said apertures, means for lowering said folder to a position in operative relation with said tucking element and 95 means for retaining it in said position.

9. In a sewing machine, a vertically movable fabric folder having an aperture through which a portion of a fabric may protrude, and means including a tucking element for inserting a second piece of fabric within said protruding portion of fabric, provision being made for relative movement between said fabric folder and the tucking element for introduction of said second piece 105 of fabric.

10. In a sewing machine comprising a cloth-plate, fabric-feeding mechanism and stitch-forming mechanism including spaced needles, a fabric-guide supported above said cloth-plate and maintained in spaced relation therewith and adapted to buckle a portion of a tapered strip of fabric passing therethrough and fold its marginal portions 110 at uniform distances from the edges thereof and direct them to the respective needles, said fabric-guide being so constructed and arranged as to permit the introduction of a second strip of fabric to the stitching mechanism beneath said first-mentioned strip and at an angle thereto, and a tucking element acting upon said last-mentioned strip to cause it to conform to the contour of the buckled portion of the first-mentioned strip 115 whereby the stitch-forming mechanism operates to stitch the folded portion of the first-mentioned strip at uniform distances from its edges, and simultaneously unite therewith, at an angle thereto, said second strip.

11. In a sewing machine constructed with 120

- a cloth-plate and comprising stitch-forming mechanism including spaced needles, a fabric-folding device with means for sustaining it above the cloth-plate and including means 5 for simultaneously turning in both marginal portions of a tapered strip of fabric and for buckling said strip in the direction of its length, said folding device being so constructed and arranged as to permit the positioning of a second strip of fabric beneath 10 said folder at an angle to said first-mentioned strip and the tucking of it into direct contact with and in the direction of the length of said first-mentioned strip, said 15 stitch-forming mechanism affording means for uniting the two strips so as to effect a uniform flat product.
12. In a sewing machine comprising stitch-forming and fabric-feeding mechanisms, in combination, a fabric-folder adapted 20 to simultaneously fold both marginal portions of a tapered strip of fabric, said folder having an aperture through which a portion of the fabric of varying amount may protrude, and means independent of said folder for inserting within said variably protruding portion a second strip of fabric and for 25 constantly maintaining their surfaces in contact.
13. In a sewing machine comprising stitch-forming and fabric-feeding mechanisms, in combination, a fabric-folder adapted to 30

multaneously fold both marginal portions of a tapered strip of fabric, said folder having an aperture through which a portion of the fabric of varying amount, may protrude, and means for inserting within said variably protruding portion a second strip of fabric and for constantly maintaining their surfaces in contact, said means including a tucking element 35 relatively movable with respect to the folder.

14. In a sewing machine comprising a cloth-plate, fabric-feeding mechanism and stitch-forming mechanism including spaced 40 needles, a fabric-folding device adapted to fold the marginal portions of a strip of fabric passing therethrough and provided with a longitudinal aperture through which a portion of the strip is free to project, said fabric 45 folding device being supported from above the cloth-plate and spaced therefrom to afford a free and unobstructed passage between the two, said stitch-forming mechanism and folding device being constructed 50 and arranged to hem the marginal portions of the strip of fabric and simultaneously unite therewith, at an angle thereto, a second strip of fabric, and a presser-foot movable relatively to said fabric-folding device. 55

In testimony whereof, I have signed my name to this specification.

ALBERT H. DE VOE.
